VANITY CASE

James L. Younghusband, Chicago, Ill.

Application March 16, 1938, Serial No. 196,226

4 Claims. (Cl. 132—82)

My invention relates to a vanity case particularly for loose powder.

It has long been a problem in the carrying of loose powder to find means to prevent the spilling of the same. This problem has not been solved by providing a door to close the powder chamber because upon opening the door the problem of spilling again arises.

Another problem is creating a construction that will provide a powder puff with just the right amount of powder for use.

Still another problem is that of supplying a structure permitting refilling of the vanity case with more loose powder after the original supply has been exhausted.

It is among the objects of my invention to provide solutions for the above and other problems and to present a vanity case adapted to hold loose powder with means having the double function of both preventing spilling of the powder as well as permitting refilling of said vanity case with loose powder. My object is also to provide a construction in which the puff is so positioned that whenever the user desires to use it it is always immediately available for use with just the right amount of powder thereon. My invention also contemplates such other objects, advantages and capabilities as will later more fully appear and which are inherently possessed by my invention.

While I have disclosed herein a preferred embodiment of my invention, yet I wish it understood that the same is merely illustrative and is susceptible of modification and change without departing from the spirit of my invention.

Referring to the drawing Fig. 1 is a perspective view of my vanity case in open position without the powder puff; Fig. 2 is a sectional view of my vanity case in closed position; Fig. 3 is a perspective view partially cut away showing my vanity case in closed position and Fig. 4 is a detail view of my cover.

Referring now more particularly to the embodiment selected to illustrate my invention it comprises a container 10 of metal plastic or any suitable material, preferably rectangular in shape, having a substantially flat bottom 11 and vertical side walls 12. Across the open top of the container is a cover 13 of rubber or of other suitable non-porous, compressible and extensible material.

The cover 13 is attached to and within the container 10 by placing the flaps 14 of said cover along the inside of the walls 12, and by then attaching a shell 15 within said container to hold said flaps. Said cover 13 may be attached to

said box by any other desirable means without departing from the spirit of my invention.

My cover 13 has a substantially centrally located slit 16, preferably of oval contour, although any shape of opening may be employed.

A removable powder puff 17 of slightly smaller size than the width and breadth of the container 10 is positioned on top of said cover 13 so as to cover slit 16 and form a seal therefor.

A cap 18 is swingably attached to container 10 by hinge 19.

Said puff 17 is of such depth and cap 18 so positioned that upon cap 18 being in normal closed position puff 17 compresses cover 13 downwardly and spreads slit 16 to a more open position. The loose powder 20 in container 10 is thus directly contacted by puff 17 so that when the user swings the cap 18 open the puff has powder on it for immediate use. The cap and the puff cooperate in advance to make the puff contact the powder. This saves the user the time and effort of an extra step heretofore necessary when the user had first to get the puff and then to apply it to the powder by manual pressure.

My construction does not have to be torn down to be refilled because the user can insert refills of loose powder through slit 16 by a spoon or any other convenient means. The slit 16 has the double function of being a dispenser as well as an entry for refills.

Upon the user finishing her toilet she replaces the puff 17 on the cover 13 over the slit 16 to form a perfect seal therefor. Then the user closes the cap 18 the puff 17 is again pressed down on the cover 13 and contacts and picks up powder 20 ready for the next use.

The cap 18 may removably fit container 10 by friction grip, screw threads or any other suitable means.

Having thus described my invention I claim:

1. A vanity case adapted to hold loose powder comprising a container having a bottom, side walls and an open top, a compressible cover attached to said container and positioned over said open top, said cover having a slit, a removable puff of smaller size than said container positioned on said cover, a cap hinged to said container, said puff being of such depth and said cap being of such thickness and so positioned that when said cap is in normally closed position said cap cooperates with said puff by pressing said puff down on said cover to spread the slit to a more open position so that said puff contacts and picks up said powder for immediate use upon the cap being moved to open position.

2. A vanity case adapted to hold loose powder comprising a receptacle portion, a compressible cover for said receptacle portion, said cover having a slit, a removable puff positioned on said cover and covering said slit, and a cap, said puff being of such depth and said cap being of such thickness and so positioned that when said cap is in normally closed position said cap cooperates with said puff by pressing said puff down on said cover to spread the slit to a more open position so that said puff contacts and picks up said powder for immediate use upon the cap being moved to open position.

3. A vanity case comprising a container adapted to hold loose powder, a compressible cover attached to said container, said cover having a slit to permit both dispensing of said powder and refilling of said container with powder, a puff positioned over said slit to seal the same, and a closure for said container, said puff being of such depth and said closure being of such thickness and so positioned that when the said closure is in normally closed position said closure cooper-

ates with said puff by pressing said puff down on said cover to spread the slit to a more open position so that said puff contacts and picks up said powder for immediate use upon the closure being moved to open position.

4. A powder dispenser comprising a container adapted to hold loose powder, a compressible cover attached to said container, said cover having a slit adapted to be spread upon pressure being applied to said cover to permit both dispensing of said powder and refilling of said container with powder, a puff positioned over said slit to normally seal the same, a cap for said container, said puff being of such depth and said cap being of such thickness and so positioned that when said cap is in normally closed position said cap cooperates with said puff by pressing said puff down on said cover to spread the slit to a more open position so that said puff contacts and picks up said powder for immediate use upon the cap being moved to open position.

JAMES L. YOUNGHUSBAND.
